United States Patent

Des. 236,787
Patented Sept. 16, 1975

236,787

BOOKCASE OR SIMILAR ARTICLE

Loren D. Stirling, Pleasanton, Calif., assignor to
Xerox Corporation, Stamford, Conn.

Filed Dec. 3, 1973, Ser. No. 420,826

Term of patent 14 years

Int. Cl. D6—04

U.S. Cl. D6—184

FIG. 1

FIG. 2

FIG. 4

FIG. 3

FIG. 6

FIG. 5

FIG. 1 is a perspective view of a bookcase or similar article showing my new design;

FIG. 2 is an elevational view taken from one side thereof;

FIG. 3 is an end elevational view thereof;

FIG. 4 is an elevational view taken from the side opposite of that shown in FIG. 2;

FIG. 5 is an end elevational view taken from the end opposite of that shown in FIG. 3;

FIG. 6 is a top plan view thereof.

I claim:

The ornamental design for a bookcase or similar article, as shown.
